H. H. HOCKETT:
INDICATING DEVICE FOR MOTOR VEHICLES.
APPLICATION FILED OCT. 2, 1915.

1,200,193.

Patented Oct. 3, 1916.

UNITED STATES PATENT OFFICE.

HARVEY H. HOCKETT, OF DALLAS, OREGON,

INDICATING DEVICE FOR MOTOR-VEHICLES.

1,200,193.

Specification of Letters Patent.

Patented Oct. 3, 1916.

Application filed October 2, 1915. Serial No. 53,844.

To all whom it may concern:

Be it known that I, HARVEY H. HOCKETT, a citizen of the United States, residing at Dallas, in the county of Polk and State of Oregon, have invented certain new and useful Improvements in Indicating Devices for Motor-Vehicles, of which the following is a specification, reference being had to the accompanying drawings.

10 This invention relates to an improved indicating device for motor vehicles and has for its primary object to provide a simple, reliable and effective means under the control of the operator of the vehicle, whereby 15 he may indicate his intentions to pedestrians and other motorists relative to his intended subsequent movements of the vehicle.

It is a more particular object of the invention to provide a rotatably mounted indicating arrow arranged upon the engine 20 hood of the vehicle, and a manually operable connection for said arrow including a shiftable rod extending through the cowl of the vehicle body in convenient relation to 25 the operator's seat.

The invention has for an additional object to provide means which will retain the indicating arrow in its adjusted position and yet permit of its easy and quick actuation when the operating rod is shifted.

With the above and other objects in view, my invention consists in the novel features of construction, combination and arrangements of parts to be hereinafter more fully 35 described, claimed, and illustrated in the accompanying drawings, in which

Figure 1 is a side elevation of a portion of a motor vehicle having my improved indicator applied thereto; Fig. 2 is a top plan 40 view; Fig. 3 is a vertical section taken on the line 3-3 of Fig. 1; Fig. 4 is a detail perspective view of the ratchet disk.

Referring in detail to the drawing, 5 designates a rod or standard which is securely attached at its lower end by means of nuts 6 to the engine hood of the vehicle.

7 designates the hollow rotatable rod or standard which is longitudinally bored at one end, as at 8, to loosely receive the upper 50 end of the vertical rod 5. The spring 5' is arranged upon the rod 5 between a head formed on the upper end of the rod and the lower end of the hollow rod 7 and normally acts to force said hollow rod downwardly.

A suitable ornamental cap 9 may be provided upon the upper end of the rotatable rod 7. This upper end portion of the rod is also provided with a longitudinally extending slot, indicated at 10, in which an arrow 11, preferably of sheet metal and 60 painted or otherwise colored, is suitably fixed.

Upon the rod 5, a disk or collar 12 is securely fixed by means of a set screw, indicated at 13. This collar is formed with an 65 upstanding flange 14 and at diametrically opposite points said flange is cut-away to form shoulders, as shown at 15 and from the bases of said shoulders, the section of the collar between the same is inclined upwardly, as at 16 to an intermediate notch or recess 17. In the lower end of the rotatable rod 7, a laterally projecting pin 18 is fixed.

19 designates the operating rod which is 75 loosely connected to the outer end of this pin. This rod is movable through the cowl of the vehicle body and may be supported at an intermediate point in an eye formed in the upper end of the standard 20 which 80 is secured at its lower end upon the engine hood.

From the above description, the operation of the device will be readily understood. Assuming that the arrow is pointing forwardly in the direction of travel of the machine, the pin 18 will then extend laterally from one side of the rod 7 at right angles to the arrow, said pin being engaged in the central notch 17 formed in the upstanding 85 flange of the disk or collar 13. Now, if it is the operator's intention to turn the machine to the left or the right, he shifts the rod 19 in one direction or the other, so that the point of the arrow will indicate the direction in which the machine will turn.

When the arrow is moved to this point, the pin 18 will strike against one or the other of the shoulders 15, so that further turning movement of the arrow is prevented. When 100 the rod is again shifted to bring the arrow back to its normal position, the pin 18 will readily ride up the inclined edge 16 of the collar flange and into the recess 17 therein, it being understood that the rod 7 will move 105 vertically from the supporting rod 5. The arrow will thus be retained in its normal position against accidental turning move-

- ment while at the same time the arrow can be easily and quickly positioned when desired, simply by shifting the operating rod 19 in the proper direction.
- 5 From the foregoing description taken in connection with the accompanying drawing, it is believed that the construction, manner of operation and several advantages of the device will be clearly and fully understood.
- 10 As the indicator is exceedingly simple in its construction, it is obvious that the same is not liable to get out of order but, on the other hand, is extremely practical in operation. The arrow may be of any desired size 15 and can be suitably ornamented, if desired. It is also apparent that other means for mounting the indicating arrow upon the vehicle may be adopted and said arrow can be also located at other points upon the 20 vehicle than the engine hood. It is, therefore, to be borne in mind that in practice, I reserve the privilege of adopting all such legitimate changes in the form, proportion and arrangement of the elements employed, 25 as may be fairly embodied within the spirit and scope of the invention, as claimed.
- Having thus described this invention,

what I desire to claim as new and secure by Letters Patent is:—

In a device of the character described, the 30 combination of a fixed support, a rod rotatably mounted upon said support, an indicating arrow fixed in said rod, a collar secured upon the support and having an upstanding flange provided with a notch and shoulders at diametrically opposite points in spaced relation to said notch, the edge of said flange being inclined upwardly from the shoulders to said notch, a pin fixed in the rotatable rod, to seat in said notch and 35 hold the rod against casual turning movement, and manually operable means connected to said pin to force the same out of the notch and rotate the rod to dispose the arrow in an operative position, said pin engaging one or the other of the shoulders to 40 limit such turning movement of the rod.

In testimony whereof I hereunto affix my signature in the presence of two witnesses.

HARVEY H. HOCKETT.
